United States Patent Office

Des. 213,754
Patented Apr. 1, 1969

213,754

BED SHEET OR SIMILAR ARTICLE OF BED LINEN

Emeric Kanitz, Paris, France, assignor to Cannon Mills
Company, Kannapolis, N.C., a corporation of North Carolina

Filed July 31, 1967, Ser. No. 8,086

Term of patent 14 years

Int. Cl. D6—09

U.S. Cl. D92—26

The reverse side of the bed sheet is substantially plain and unornamented.

I claim:

The ornamental design for a bed sheet or similar article of bed linen, substantially as shown and described.
